UNITED STATES PATENT OFFICE.

MAX GOLDFARB, OF NEW YORK, N. Y.

DESIGN FOR A RADIO HORN.

Application filed June 7, 1922. Serial No. 2,561. Term of patent 3½ years.

To all whom it may concern:

Be it known that I, MAX GOLDFARB, a citizen of the United States, residing in the city of New York, borough of the Bronx, in the county of Bronx and State of New York, have invented a new, original, and ornamental Design for Radio Horns, of which the following is a specification, reference being had to the accompanying drawings, forming a part thereof, and of which—

Figure 1 is a front elevation, and Fig.

2 is a side elevation of a radio horn showing my new design.

I claim:

The ornamental design for a radio horn as shown.

MAX GOLDFARB.
